ABSTRACT OF THE DISCLOSURE

Photographic materials comprising a light-sensitive silver halide emulsion element containing an azaindene emulsion stabilizing agent in contact with as an additional stabilizing agent an amide having the formula:

wherein

each of R_1 and R_2 stands for hydrogen, lower alkyl, lower alkyl carrying a hydroxyl group, lower alkyl carrying the group R_3CONH- , or a phenyl group, R_1 together with R_2 stands for the atoms necessary to close a pyrrolidine, piperidine or morpholine nucleus, R_3 stands for lower alkyl or the group

wherein each of R'_1 and R'_2 have the same significance as R_1 and R_2 , R'_1 and R'_2 both being different from hydrogen, or R_3 may represent hydrogen when R_1 or R_2 is substituted alkyl, or R_3 together with R_2 stands for alkylene.

A synergistic effect is obtained with regard to fog inhibition particularly upon storage of the element.

This invention relates to improved photographic materials comprising light-sensitive silver halide emulsions, more particularly to photographic materials having less tendency to fog formation and showing no appreciable desensitization upon storage.

It is well known that light-sensitive silver halide materials comprising gelatin silver halide emulsion layers are subject to fogging. Fogging in general and chemical fogging in particular may be defined as the formation of a uniform deposit of silver on processing which is dependent on a whole series of circumstances and factors namely on the nature of the emulsions, on their age, on the conditions under which they have been stored, on the processing conditions, etc. For particular processing conditions the fog tends to be greater as the time of storage and the temperature and relative humidity of the atmosphere, in which the emulsions are stored, are increased.

Addenda to the photographic material known as stabilizers or antifogants protect the light-sensitive silver

2

halide emulsions against formation and growth of fog particularly in high-sensitive emulsions and in emulsions which are stored under adverse conditions of temperature and humidity as is for instance the case in tropical countries. Among these addenda the azaindene stabilizing agents are widely used because of their unique properties in stabilizing the emulsions against the development of this general fog without giving rise to an appreciable desensitization.

It has now been found that the stability of light-sensitive silver halide emulsions comprising azaindene stabilizing agents against growth of fog can still be improved by the use of amide compounds corresponding to the formula:

or polymers comprising recurring units of the formula:

wherein

each of R_1 and R_2 stands for hydrogen, alkyl preferably comprising at most 5 C-atoms including substituted alkyl such as hydroxylalkyl and the group R_3CONH- alkyl, or aryl including substituted aryl, or R_1 together with R_2 represent the atoms necessary to close a pyrrolidine, piperidine or morpholine nucleus, R_3 stands for alkyl preferably comprising at most 5 C-atoms, for the group

wherein each of R'_1 and R'_2 have the same significance as R_1 and R_2 , R'_1 and R'_2 both being different from hydrogen however, or R_3 may represent hydrogen when R_1 or R_2 stands for substituted alkyl in particular R_3CONH -alkyl,

or R_3 together with R_2 stand for alkylene, preferably alkylene comprising at least 3 methylene groups such as pentamethylene, R_1 then being preferably hydrogen, and

R_4 stands for hydrogen or lower alkyl such as methyl, as additional stabilizing agents, the sensitivity not being influenced to a noteworthy extent.

Thus, in accordance with the present invention photographic emulsions are provided which are stabilized with azaindene and additionally stabilized with amide compounds corresponding to the above general formulae.

Exemplary compounds corresponding to the above general formulae that are suitable for use with azaindene stabilizing agents in light-sensitive silver halide emulsions are:

 (1) acetamide H_3CCONH_2
65

- (3) dihydroxyethyl acetamide $\text{H}_3\text{CCON}(\text{CH}_2\text{CH}_2\text{OH})_2$
- (4) tetramethylurea $\text{H}_3\text{C}-\text{N}(\text{CONH}_2)-\text{CH}_3$
- (5) propionamide $\text{CH}_3\text{CH}_2\text{CONH}_2$
- (6) butyramide $\text{CH}_3\text{CH}_2\text{CH}_2\text{CONH}_2$
- (7) ϵ -caprolactam $\text{H}_2\text{C}-\text{CH}_2-\text{CO}-\text{CH}_2-\text{CH}_2-\text{NH}-\text{CH}_2-\text{CH}_2-\text{CH}_2$
- (8) poly(*N*-acrylmorpholine) having recurring units of the formula:

and having an intrinsic viscosity of 0.134 dl./g.⁻¹ measured at 25° C. in tetrahydrofuran, prepared by refluxing a 10% by weight solution in methanol of the monomer in the presence of 5% by weight relative to the monomer of azobisisobutyronitrile as initiator.

- (9) acetanilide $\text{H}_3\text{CCONH}-\text{C}_6\text{H}_4-\text{CH}_3$
- (10) $\text{OHCNHCH}_2\text{CH}_2\text{NHCHO}$

The amide compounds of use according to the present invention are preferably incorporated into the silver halide emulsion layer comprising azaindene stabilizer of the light-sensitive material. The way in which the azaindene and amide compounds of use according to the invention are added to emulsions is not critical and the addition may occur during no matter what step of emulsion preparation.

The preparation of silver halide emulsions involves three separate operations: (1) the emulsification and digestion or ripening of the silver halide, (2) the freeing of the emulsion from aqueous soluble salts usually by washing, and (3) the second digestion or after ripening (chemical ripening) to obtain increased sensitivity.

The azaindene and amide compounds of use according to the present invention can be added before or after the emulsion has been optically sensitized, preferably just before coating of the emulsion on a suitable support such as for example paper, glass or film such as cellulose triacetate and polyethylene terephthalate.

Instead of incorporating the amide compounds of the invention into the emulsion layer comprising azaindene stabilizer they can also be incorporated into another layer of the photographic material, e.g. a gelatin anti-stress layer or intermediate layer, which is in water-permeable relationship with the said emulsion layer or into one of the processing baths for said photographic material.

The amide stabilizers of use according to the present invention may be used in conjunction with azaindene stabilizers in any type of light-sensitive material e.g. spectrally sensitized or non-sensitized silver halide material, silver halide material of use in diffusion transfer processes for the production of silver images, and X-ray material. They may be used in high speed negative materials as well as into rather low speed positive materials. Various silver salts may be used as light-sensitive salt e.g. silver bromide, silver iodide, silver chloride, or mixed silver halides e.g. silver chlorobromide or silver bromoiodide.

The silver halides are dispersed in the common hydrophilic colloids such as gelatin, casein, zein, polyvinyl alcohol, carboxymethylcellulose, alginic acid, etc., gelatin being, however, favoured.

The amount of amide compound employed in the light-sensitive silver halide material depends on the particular type of emulsion and the desired effect and can vary within very wide limits. The optimum amount of amide compound to be added is best determined for each particular type of emulsion by trial. Generally, the most suitable concentration is between 0.5 g. and 20 g. of amide compound per mole of silver halide.

The azaindene stabilizing agents used in the silver halide emulsions in concentrations as known in the art which are of the order of from 0.02 gram to 10.0 grams, preferably from 0.1 and 5 g. per mole of silver halide.

Azaindene stabilizing agents for use in light-sensitive silver halide material are widely known in the art. Examples of azaindene stabilizing agents can be found in literature amongst others in U.S. Pat. 2,944,902 and the patent literature referred to therein for that purpose. They include amongst others the hydroxy tetraazaindene corresponding to the formula:

wherein:

each of R_4 and R_5 stands for hydrogen, alkyl, aralkyl and aryl, and
 R_6 stands for hydrogen, alkyl, carboxy or alkoxy carbonyl.

By way of example, 5-methyl-7-hydroxy-s-triazolo[1,5-a]pyrimidine, 6-carboxy-7-hydroxy-s-triazolo[1,5-a]pyrimidine, 6 - carbethoxy - 7 - hydroxy-s-triazolo[1,5-a]pyrimidine and 2- β -hydroxyethyl-5-methyl-7-hydroxy-s-triazolo[1,5-a]pyrimidine can be mentioned as suitable hydroxy tetraazaindenes.

The light-sensitive emulsions may be chemically as well as optically sensitized. They may be chemically sensitized by any of the accepted procedures. The emulsions may be digested with naturally active gelatin or sulphur compounds may be added such as allyl thiocyanate, allyl thiourea, sodium thiosulphate, etc. The emulsions may also be sensitized by means of reductors for instance tin compounds as described in our British patent specification 789,823 and by means of small amounts of noble metal compounds such as of gold, platinum, palladium, iridium, ruthenium and rhodium. Representative compounds are ammonium chloro palladate, potassium chloroplatinate, potassium chloroaurate and potassium aurithiocyanate. These sensitizers can be added during no matter what step of emulsion preparation e.g. before, during or after the chemical ripening.

Other addenda such as hardening agents e.g. formaldehyde, dialdehydes, halogen substituted aldehyde acids such as mucochloric and mucochromic acid, etc., wetting agents, plasticizers, colour couplers, developing agents and optical sensitizers can be incorporated into the emulsion in the usual way.

The azaindene and amide compounds of use according to the present invention are particularly suitable for use in conjunction with compounds which sensitize the emulsion by development acceleration for example alkylene oxide polymers. These alkylene oxide polymers may be of various type. Various derivatives of alkylene oxides may be used to sensitize the silver halide emulsions, e.g. alkylene oxide condensation products as described among others in United States patent specifications 2,531,832 and 2,533,990, in United Kingdom patent specifications

920,637, 940,051, 945,340 and 991,608 and in Belgian patent specification 648,710. Other compounds that sensitize the emulsion by development acceleration and that are suitable for use in combination with the azaindene and amide compounds of use according to the invention are the onium derivatives of amino-N-oxides as described in United Kingdom patent specification 1,121,696.

The emulsions may further comprise other known antifoggants or stabilizers for instance heterocyclic nitrogen containing thioxo compounds such as benzothia-

Development occurred for 6 min. at 20° C. in a developing bath having the following composition:

Water	ml	800
p-Monomethylamino phenol sulphate	g	4
Sodium sulphite (anhydrous)	g	65
Hydroquinone	g	10
Sodium carbonate (anhydrous)	g	45
Potassium bromide	g	5
Water to make 1000 ml.		

TABLE

Compound(s) added per kg. emulsion	Fresh material			Stored material		
	Fog	γ	Relative speed	Fog	γ	Relative speed
0.600 g. of azaindene 1 (a)	0.04	2.30	100	0.15	1.93	105
8 g. of compound 1 (b)	0.07	2.59	145	2.85		
(a) plus (b)	0.03	2.46	102	0.11	2.12	107
8 g. of compound 6 (c)	0.06	2.58	145	2.88		
(a) plus (d)	0.03	2.63	102	0.11	2.30	110
8 g. of compound 3(d)	0.09	2.34	200	3.15		
(a) plus (b)	0.02	2.62	105	0.13	2.25	126
8 g. of compound 5(e)	0.08	2.43	123	2.51		
(a) plus (e)	0.03	2.60	100	0.12	2.30	110
8 g. of compound 8(f)	0.74	2.00	81	2.15		
(a) plus (f)	0.08	2.90	123	0.11	2.49	118

¹ The azaindene stabilizer used in the above materials is 5-methyl-7-hydroxy-s-triazolo [1,5-a] pyrimidine.

zoline-2-thione and 1-phenyl - Δ_2 - tetrazoline-5-thione, mercury compounds such as those described in Belgian patent specifications 525,121 and 677,337 and in Belgian patent specifications 707,386 and 709,195 and salts such as cadmium chloride, cadmium nitrate, cobalt nitrate, manganese chloride, zinc chloride and zinc nitrate, sulphuric acids such as benzene sulphuric acid and toluene sulphuric acid, thiosulphonic acids such as benzene thiosulphonic acid, toluene thiosulphonic acid, p-chloro-benzene thiosulphonic acid sodium salt, propyl thiosulphonic acid potassium salt, butyl thiosulphonic acid potassium salt, etc. These thiosulphonic acid compounds are particularly suitable for use in emulsions ripened

30 From the above results appears that when using in azaindene stabilized emulsions the amide compounds according to the invention fog formation is still reduced, especially upon storage, though these compounds, when used alone, give high fog values upon storage.

EXAMPLE 2

35 Example 1 is repeated with the difference, however, that development now took place for 20 sec. at 40° C. in the tanning 1 - phenyl - 3-pyrazolidinone/hydroquinone developer "G 137" marketed by Gevaert-Agfa N.V. Belgium.

The sensitometric results attained are listed in the table 40 below.

Compound(s) added per kg. emulsion	Fresh material			Stored material		
	Fog	Gradation	Relative speed	Fog	Gradation	Relative speed
0.600 g. of the azaindene compound of example 1(a)	0.05	1.87	100	0.12	1.29	63
(a) plus 8 g. of compound 1	0.03	2.01	102	0.09	1.33	71
(a) plus 8 g. of compound 3	0.03	1.95	102	0.08	1.59	93
(a) plus 8 g. of compound 5	0.02	2.08	105	0.09	1.41	72
(a) plus 8 g. of compound 6	0.03	2.19	107	0.09	1.47	76
(a) plus 8 g. of compound 8	0.06	1.77	73	0.07	1.59	60

55 with noble metal compounds or reducing agents and are, unlike the sulphuric acids, fully compatible with hardening by means of mucochloric and mucobromic acid.

The following examples illustrate the present invention.

EXAMPLE 1

An orthochromatic ammoniacal silver bromoiodide emulsion (2.75% of iodide), for photography of the green fluorescent screen, which comprises per kg. an amount of silver halide equivalent to 180 g. of silver nitrate and 72 g. of gelatin, was divided into several portions. To each of these portions the compounds listed in the table below were added in the amount given, prior to coating on a conventional film support.

The values of speed, gradation and fog of the materials formed were determined shortly after preparation and after having been stored for 36 hours at 57° C. and 34% relative humidity.

These values are listed in the table below. The values of the speed are relative values with respect to the speed of the material comprising only 5-methyl-7-hydroxy-s-triazolo[1,5-a]pyrimidine to which the value 100 is given (fresh material).

55 From these results too it appears that the amide compounds of the invention reduce fog formation in azaindene-stabilized emulsions.

EXAMPLE 3

A gelatino silver bromoiodide emulsion (2 mole percent of iodide) comprising per kg. an amount of silver halide equivalent to 180 g. of silver nitrate and 72 g. of gelatin was divided into several portions. To each of these portions the compounds listed in the table below were added in the amount given, prior to coating on a conventional film support.

65 The values of speed, gradation and fog of the materials formed were determined shortly after preparation and after having been stored for 36 hours at 57° C. and 34% of relative humidity by exposure to X-rays with an X-ray radiation source of 80 kv. and development for 4 min. at 20° C. in a common X-ray developer having the composition given in Example 1.

70 The values attained are listed in the table below. The values of the speed are relative values with respect to the speed of the material comprising only 5-methyl-7-hydroxy-s-triazolo[1,5-a]pyrimidine to which the value 100 is given (fresh material).

Compound(s) added per kg. emulsion	Fresh material			Stored material		
	Fog	Grada- tion	Relative speed	Fog	Grada- tion	Relative speed
0.600 g. of the azaindene com- ound of Example 1 (a)-----	0.11	2.88	100	0.24	2.16	128

We claim:

1. Photographic material comprising a light-sensitive, developing-out, silver halide emulsion layer containing an azaindene emulsion stabilizing agent having the formula:

wherein:
each of R₄ and R₅ stands for hydrogen, alkyl, aralkyl and aryl, and R₆ stands for hydrogen, alkyl, carboxy or alkoxy carbonyl,

said material comprises in the said emulsion layer or in another colloid layer in water-permeable relationship

R₁ together with R₂ stands for the atoms necessary to close a pyrrolidone, piperidine or morpholine nucleus, R₃ stands for lower alkyl or the group

65 wherein each of R'₁ and R'₂ have the same significance as R₁ and R₂, R'₁ and R'₂ both being different from hydrogen, or R₃ may represent hydrogen when R₁ or R₂ is substituted alkyl, or

R₃ together with R₂ stands for alkylene.

2. Photographic material according to claim 1, where-
in said amide compound corresponds to the formula:

wherein:

R_1 stands for hydrogen, and
 R_3 together with R_2 stands for alkylene.

3. Photographic material according to claim 1, wherein said amide compound corresponds to the formula:

wherein:

R_1 stands for hydrogen or lower alkyl,
 R_2 stands for lower alkyl carrying the group $R_3\text{CONH}-$, and
 R_3 stands for hydrogen or lower alkyl.

4. Photographic material according to claim 1, wherein said amide compound is present in the azaindene stabilized emulsion layer.

5. Photographic material according to claim 1, wherein said azaindene is 5-methyl-7-hydroxy-s-triazolo pyrimidine.

6. Photographic material according to claim 1, wherein the said emulsion layer comprises a development accelerator of the polyoxyalkylene type.

7. Photographic material according to claim 1 wherein said amide compound corresponds to the formula:

wherein:

each of R_1 and R_2 stands for hydrogen, lower alkyl, hydroxy-substituted lower alkyl, or phenyl, and
 R_3 stands for lower alkyl, or

each of R'_1 and R'_2 being lower alkyl, hydroxy-substituted lower alkyl or phenyl.

8. Process for inhibiting fog-formation in photographic silver halide materials comprising a support carrying water-permeable colloid layers including a silver halide emulsion layer, which comprises an azaindene emulsion stabilizing agent having the formula:

wherein:

each of R_4 and R_5 stands for hydrogen, alkyl, aralkyl and aryl, and R_6 stands for hydrogen, alkyl, carboxy or alkoxy carbonyl,

which process comprises processing the said material after image-wise exposure in the presence of an amide compound corresponding to the formula:

wherein:

each of R_1 and R_2 stands for hydrogen, lower alkyl group, lower alkyl carrying a hydroxyl group, lower alkyl carrying the group $R_3\text{CONH}-$, or a phenyl group,

R_1 together with R_2 stands for the atoms necessary to close a pyrrolidone, piperidine or morpholine nucleus, R_3 stands for lower alkyl or the group

wherein each of R'_1 and R'_2 have the same significance as R_1 and R_2 , R'_1 and R'_2 both being different from hydrogen, or R_3 may represent hydrogen when R_1 or R_2 is substituted alkyl, or
 R_3 together with R_2 stands for alkylene.

9. Process according to claim 8, wherein said amide compound corresponds to the formula:

wherein:

10 R_1 stands for hydrogen, and
 R_3 together with R_2 stands for alkylene.

10. Process according to claim 8, wherein the said azaindene is 5-methyl-7-hydroxy-s-triazolo pyrimidine.

11. Process according to claim 8, wherein said amide compound corresponds to the formula:

30 wherein:

R_1 stands for hydrogen or alkyl,
 R_2 stands for the group $R_3\text{CONH}-$, and
 R_3 stands for hydrogen or alkyl.

35 12. Process according to claim 8 wherein said amide compound corresponds to the formula:

wherein:

each of R_1 and R_2 stands for hydrogen, lower alkyl, hydroxy-substituted lower alkyl or phenyl, and

45 R_3 stands for lower alkyl, or

50 each of R'_1 and R'_2 being lower alkyl, hydroxy-substituted lower alkyl or phenyl.
